(57) **CLAIM**

I claim the ornamental design for a bicycle saddle, as shown.

DESCRIPTION

FIG. 1 is a top perspective view of a bicycle saddle of my new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof; and,

FIG. 8 is a bottom perspective view thereof.

The gray shading shown is intended to represent the contours of the design and is not representative of any particular color.

1 Claim, 5 Drawing Sheets
